UNITED STATES PATENT OFFICE.

ALBERT D. SCHNAARS, OF JERSEY CITY, NEW JERSEY, AND CHARLES L. JOLY, OF NEW YORK, N. Y.

TRAFFIC-SIGNAL FOR VEHICLES.

1,172,060.

Specification of Letters Patent. Patented Feb. 15, 1916.

Application filed March 11, 1914. Serial No. 824,042.

To all whom it may concern:

Be it known that we, ALBERT D. SCHNAARS, a citizen of the United States, and a resident of Jersey City, in the county of Hudson and State of New Jersey, and CHARLES L. JOLY, a citizen of the United States, and a resident of the city of New York, Tottenville, borough of Richmond, in the county of Richmond and State of New York, have invented a new and Improved Traffic-Signal for Vehicles, of which the following is a full, clear, and exact description.

Among the principal objects which the present invention has in view are: to provide means whereby cautionary and directive signals are automatically disclosed coincident with the operation of a manually guided and controlled vehicle; to provide a device of the character indicated, having a containing case for normally concealing the directive members, said case being reduced in its structural dimensions; to provide means whereby the stop indication is preceded by a cautionary indication; and to provide for duplicating certain of the signals at the front end, as well as at the rear of the vehicle.

Drawings.—Figure 1 is a side view indicating in light lines a vehicle of the character mentioned, having applied thereto signals constructed and arranged in accordance with the present invention, the elements employed in the present invention being indicated by heavy lines; Fig. 2 is a face view of the front end signal apparatus forming a part of the present invention; Fig. 3 is a vertical cross section taken as on the line 3—3 in Fig. 2, showing in conjunction therewith a water-cooling radiator of conventional construction, and means for mounting the same on said radiator; Fig. 4 is a sectional view on an enlarged scale, taken on the line 4—4 in Fig. 3, showing in detail the means for normally disposing a pointer used in the signal; Fig. 5 is a face view of the rear end signal apparatus employed in the present invention; Fig. 6 is a vertical cross section of the rear end signal apparatus, the section being taken on the line 6—6 in Fig. 5; Fig. 7 is a vertical longitudinal section of the rear end signal, the section being taken as on the line 7—7 in Fig. 6; Fig. 8 is a longitudinal cross section on an enlarged scale, taken as on the line 8—8 in

Fig. 7; Figs. 9, 10 and 11 are detail views 55 on enlarged scale, showing in cross section the operating shaft and the "slow" signal in conjunction therewith; Fig. 12 is a vertical cross section of the pivot housing for the pointer used in the rear end signal. 60

Description.—As shown in the accompanying drawings, a signal apparatus 15 is mounted on the front of a vehicle, and preferably, when the vehicle is an automobile, on the face of the radiator thereof. As 65 shown in Fig. 2 of the drawings, the apparatus 15 has a face plate 16, whereon are placed visible symbols indicating a normal position and positions to the right and left thereof. An oscillating pointer 17 is mounted upon a shaft 18, which is rocked in suitable bearings, one being disposed in a bracket plate 19, and the other at the rear thereof in a plate 20. The shaft 18, when rocked, disposes the pointer 17 in one of 75 the three positions indicated in Fig. 2 of the drawings.

The shaft 18 is provided with a crank arm 21, in the perforation 22 whereof is entered a transmission cable 23. The cable 80 23 is operatively engaged with the steering bar 24 of any suitable conventional motor-driven vehicle. The cable 23 is split, the sections being connected by a spring 25 under tension. The spring 25 operates to take 85 up any slack which may obtain in the cable. Normally, the spring 25 pulls against a coil spring 26, which spring is wrapped on the shaft 18 or hub of the pointer 17, and has a bearing on the side of the plate 19. The 90 function of the spring 26, if unrestricted, would normally dispose the pointer 17 in position to one side or the other of the normal or central position indicated on the plate 16. 95

In the steering gear of an automobile, a certain amount of lost motion is generally provided for between the steering wheels and the tiller post. This fact is taken advantage of in the present invention, as by 100 means of this the tiller post may be moved sufficiently to vary the pressure on the cable 23, and thereby dispose the pointer, with the aid of the spring 26, in any of the three positions indicated by markings on the 105 plate 16. To this end, the driver of an automobile having a signal constructed and arranged in accordance with the present in-

vention, shifts his steering wheel and incidentally the steering bar 24, preliminary to making the desired turn. In doing this, the signal apparatus 15 which is at the front of the vehicle, is moved in consonance with the shaft of the steering wheel, and simultaneously a pointer 27 of a signal apparatus 28 at the rear of the vehicle, is shifted to give the same indication rearwardly as that imparted forwardly by the pointer 17.

The pointer 27 is identical with the pointer 17 in construction and in the manner in which it is harnessed or connected to the steering bar 24. For the purpose of distinguishing the cables operating the two pointers, the numeral 29 is used to indicate the rearward cable, which, at the rear of the machine, enters the casing forming the signal apparatus 28. The pointer 27 is provided with a coil spring 26, a duplicate of the coil spring provided to operate the pointer 17. Also, the cable 29 is provided with a take-up spring 25, a duplicate of the spring with which the cable 23 is provided. It will be understood that the arrangement of the cables 23 and 29 and the elements connected therewith, and that the pointers 17 and 27, are such that the two pointers are operated to convey the same information when viewed from the front or from the rear of a vehicle constructed in accordance with the present invention.

The target section 30 is loosely mounted upon a sleeve 32, and the target section 31 is fixedly mounted upon said sleeve. The normal or collapsed position of the two sections is controlled by a coil spring 33. In the collapsed position, the aperture or transparency 34 is obscured or blotted out by the interposition of said sections between the transparency and the lamp 35 with which the signal is provided.

A single-membered target 36 is fixedly mounted on a sleeve section 37. The sleeve 32 and the section 37 are of the same diameter, and the edges are arranged to bear against each other. The two sections are connected by a tube 38, which is loosely mounted on the section 37.

The normal or retracted position of the tube 38 is controlled by a coil spring 39 which is wrapped on section 37. The tube 38 is moved positively to position by means of an operating cable 40. The cable 40, as shown in Fig. 1 of the drawings, is operatively connected with a foot lever 41 and with an emergency brake 42.

The tube 38 is provided with an elongated slot 43, through which a tab 44 on the sleeve 32 extends. The purpose of the tab 44 is to provide means by which the tube 38, after rotating through a single arc of movement, engages the sleeve 32 to move into functional position the target sections 30 and 31. It will be seen that the target

section 31 which is lifted preliminary to the lift of the target section 30, carries on its face the letters "OP", and that the target section 30 carries on its face the letters "ST", said letters being combined in the exposed or lifted position to produce the word "STOP". On the end of the target member 36 is printed the word "SLOW". The normal position of the parts herein enumerated is the recumbent position, or one where the target member 36 and the target sections 30 and 31 are both concealed or lying prone within the box of the signal 28. Also, it will be noted that the pointer 27 is vertically disposed and held midway between the letters "L" and "R".

The method of moving the pointer 27 to indicate a proposed variation of the path of travel of the vehicle, has been described above. When, in the control of the vehicle, it is desired to lessen the speed or arrest the vehicle, the foot brake 41, or the emergency brake 42, is manipulated. In other words, power to this effect is applied to the cable 40. A preliminary movement is thereby effected in the section 37 and tube 38, lifting immediately the target member 36 to expose the symbol "SLOW". If it be the intention to merely diminish the speed, the lever 41 is held in this position, and the tube 38 has been rotated to the point where it is juxtaposed to, or merely engaged with the tab 44. If now the brake lever 41, or the emergency lever 42 be employed to firmly set the brakes to arrest the progress of the vehicle, the tube 38 is further revolved, engaging the tab 44 and the sleeve 32 thereby, to rotate the same. The immediate effect of the rotation of the tube 32 is to lift the target section 31, which in turn engages and lifts the target section 30, the two sections being then raised into view, to expose the symbol "STOP".

It will be understood that when the target 36 is lifted to the upright position, it is there arrested by a shoulder formed on the casing, and is thereafter held in upright position while the target sections 30 and 31 are being lifted to service position, in which position, as shown by dotted lines in Fig. 7, the connecting spring 49 yields to permit the continued rotation of the tube 38 required to set the sections 30 and 31.

It will be understood that the targets 36 and 30-31 are employed in conjunction with the rear end signal apparatus 28, and not in conjunction with the front signal apparatus 15. The signal targets are each returned to their out-of-service position by the coil springs 33 and 39 when permitted by releasing the foot brake 41 or the emergency brake 42, as the case may be.

As will be seen in the drawings, the lamp 35 is mounted in the containing case of the apparatus 28 and in line with the "ruby" 130

or riding light 45. The lamp 35 serves at night to illuminate the interior of the containing case and the aperture or transparency 34. The transparency 34 has imprinted or otherwise impressed thereon the word "STOP". When the target sections 30 and 31 are lifted in the night, they are not readily seen, and at this time the word on the transparency is employed as a substitute or 10 alternative. In the assembled containing case, a slot is formed in the top thereof by the recess 46. Said slot is sufficiently wide to permit the light furnished by the lamp 35 to illuminate a plate 47, which, in the apparatus 28, constitutes the duplicate of the plate 16 in the apparatus 15. In this manner, provision is made for utilizing the pointer 27 by night as well as by day, while the target members directly employed as 15 day signals only, being replaced at night by the transparency 34, for which, however, said target sections serve as a curtain when in out-of-service position.

The upper and lower walls of the casing 25 of the apparatus 28 are perforated suitably to admit light to the target 36 on which is imprinted the word "SLOW", and also to the license number plate 48. In this manner, the lamp 35 serves the purpose of a

riding lamp, as well as for the illumination 30 of the signal plates.

Claim:

A signal as characterized, comprising a stationary concealing member of contracted width; a single membered target having a 35 speed reduction indicating symbol pivotally mounted to swing around a supporting shaft, to expose the symbols thereon, the width of said target being approximately the width of said concealing member; a 40 fractional membered target having a speed suspension indicating symbol, the fractions of said target being adapted to spread in surface to cover the single membered target; and means embodying the brake controlling 45 mechanism of an automobile operatively connected with said targets to move the same successively to the service position thereof.

In testimony whereof we have signed 50 our names to this specification in the presence of two subscribing witnesses.
